REINFORCED BUILDING FABRIC

Filed Aug. 6, 1923

INVENTOR:

Edwin D. Coddington,

Bottum, Hinckley, Lecher McNamee &
ATTORNEYS.

UNITED STATES PATENT OFFICE

EDWIN D. CODDINGTON, OF NORTH MILWAUKEE, WISCONSIN

REENFORCED BUILDING FABRIC

Application filed August 6, 1923. Serial No. 655,917.

This invention relates to improvements in reenforced building fabric of the class and for the same general purposes as that shown and described in United States Letters Patent 5 No. 1,164,334, issued to me December 14, 1915, and in my pending application Serial No. 537,717, filed February 20, 1922.

The main objects of the invention are to further stiffen such fabric; to facilitate the 10 application of plaster thereto; to admit of the use of thinner coatings of plaster and hence effect a saving of plaster; to provide for a more effective bonding of the plaster to the fabric; and generally to improve the 15 construction of fabric of this class.

It consists in the construction, arrangement and combination of parts as hereinafter particularly described and pointed out in the claims.

20 In the accompanying drawing like characters designate the same parts in the several figures.

Figure 1 is a face view of a piece of reenforced fabric embodying the invention; Fig. 25 2 is a section on the line 2-2, Fig. 1; Fig. 3 is an enlarged cross section of one of the auxiliary metal reenforcing strips; Fig. 4 is a face view similar to Fig. 1 of a piece of 30 reenforced fabric embodying the invention in a modified construction; and Fig. 5 is a section on the line 5-5, Fig. 4.

Referring to Figs. 1, 2 and 3, the fabric comprises a flexible sheet *a*, of suitable fibrous material such as the wellknown building felt 35 of commerce, which is ordinarily and preferably saturated or coated with tar, asphalt or the like, to make it impervious to moisture.

The sheets are reenforced at suitable intervals with hard drawn, resilient, or annealed or partially annealed and more or less flexible metal wires *b*, which are woven in and out through the sheet. The reenforcing wires may run crosswise of the sheet parallel 40 with one another and with opposite ends or sides of the sheet, but may be variously arranged and placed as illustrated in said Letters Patent, according to the nature and purpose of the structure to which the fabric is 45 to be applied.

Between one side of the sheet *a* and the wires *b*, auxiliary metal reenforcing and stiffening strips *c* are inserted transversely to the wires which impart an undulatory form to the sheet.

It has been found that in applying plaster to the reenforcing fabric the trowel presses the portions of sheet *a* between members *c* inwardly. When the trowel passes over the portions of sheet *a* between reenforcing members *c*, these portions spring outwardly again to assume their former position, and in so doing dislodge the plaster which has just been applied by the trowel. To prevent this bulging or springing action of the portions 55 of sheet *a* between reenforcing members *c*, and to increase the stiffness and stability of the sheet between members *c*, the reenforcing wires *b* are woven through sheet *a* at a plurality of points, or at closer intervals or in 60 shorter stitches intermediate reenforcing members *c*, as shown in Fig. 1, to provide a stitch or a number of stitches between these members.

It has been found from experience that 70 this weaving of wires *b* through the portions of sheet *a* between reenforcing members *c* makes it possible to readily apply plaster to the fabric so that a fewer number of coats 75 of plaster are needed to make a satisfactory job.

Satisfactory results have been obtained by 80 weaving wires *b* through sheet *a*, as shown in Fig. 1, to make a double stitch through the portions of sheet *a* between reenforcing members *c*.

The strips or members *c* are corrugated lengthwise to stiffen them, being formed with a central rib *d*, which is placed next to the sheet, and with marginal wings or flanges *e*, overhanging the sheet at a distance therefrom, to receive plaster between them and the sheet and form clenches or bonds therewith.

At the junction of the flanges *e* with the 95 sides of the ribs *d* are formed small outwardly projecting beads or ridges *f*, to which the overlying reenforcing wires *b* are secured at suitable intervals, as shown at *g* in Figs. 1 and 2, by electric welding or soldering, the 100

beads or ridges limiting the initial area of contact between the wires and strips *c* and facilitating the welding or soldering of the parts together and preventing breaking down, weakening or injury of the thin metal strips by excessive heating. Thus rigidly fastening the wires *b* to the strips *c* at intersections thereof, prevents them from slipping upon one another, and materially stiffens the fabric, enabling it to resist the pressure of tools used in the application of plaster thereto without flexure or displacement of the fabric, facilitating the application of the plaster and admitting of the use of a thinner coating of plaster.

Referring to Figs. 4 and 5, showing a modification of the fabric, the auxiliary re-enforcing and stiffening strips *c'* are made of wood, and are fastened at intervals to the overlying reenforcing wires *b* so as to prevent their slipping or displacement relative thereto, as by staples *g'*.

The fabric constructed in either of the ways shown and described, is made in sheets or sections of any convenient or desired dimensions, which can be piled or stacked flat, one upon another, and bundled in small compass for storage and transportation and in the most convenient condition for immediate application to a building.

In laying the sheets, they are lapped at the edges and fastened to the studding or frame members *h* of the structure to which they are applied, in any suitable manner, as set forth in said Letters Patent, or otherwise.

In either construction, the strips *c* or *c'* being fastened at intervals to the wires *b*, are held to the wires so that the plaster when applied to the fabric, will push the flexible sheets slightly away from the backs of the strips, and will pass between them and the sheets and thus completely surround and imbed the strips in the plaster, avoid air pockets, and form the most effective clenches or bonds between the plaster and fabric, besides protecting the strips from the air and preventing their corrosion or disintegration.

The reenforcing members of the fabric fastened together at intersections, so that they will not shift their positions relative to one another, anchor the plaster in which they are imbedded and prevent it while in a plastic condition, from sliding out of place or shifting on the fabric.

The plaster filling the deeper depressions in the sheets adjacent the auxiliary stiffening strips *c* or *c'*, forms on the back of the plaster coating next to the sheets, corrugations or ribs which also materially stiffen and strengthen the finished structure without correspondingly increasing the quantity of plaster required to properly coat the fabric.

The auxiliary ribbed metal reenforcing strips *c* facilitate fastening the fabric to the studding or frame work of a structure by

nailing according to customary practice of lathers, the nails, indicated at *j*, Fig. 2, being centered and guided in driving by the grooves formed in the outer faces of the strips by the ribs *d*.

Various modifications in details of construction and arrangement of parts of the fabric, other than those specified, may be made without departure from the principle and scope of the invention as defined in the following claims. For example, the shape and arrangement of the metal auxiliary re-enforcing and stiffening strips *c* may be varied and in some cases they, or some of them, may be placed outside of the wires *b* and welded, soldered or otherwise rigidly fastened thereto at intersections therewith.

I claim:

1. A reenforced building fabric comprising a flexible sheet of fibrous material, metal reenforcing wires woven at intervals through the sheet and forming undulations therein transversely to the wires, and auxiliary reenforcing and stiffening members disposed transversely to the wires and deepening the undulations in the sheet adjacent thereto, said members being secured at intervals to the wires by non-slip fastenings.

2. A reenforced building fabric comprising a flexible sheet of fibrous material, metal reenforcing wires woven at intervals through the sheet and forming undulations therein transversely to the wires, and auxiliary metal reenforcing and stiffening strips inserted between the sheet and wires and each formed with a longitudinal rib next to the fabric and marginal wings overhanging the sheet and adapted to form clenches with a plaster coating.

3. A reenforced building fabric comprising a flexible sheet of fibrous material, metal reenforcing wires woven at intervals through the sheet and forming undulations therein transversely to the wires, and auxiliary metal reenforcing strips each formed with a rib next to the sheet and marginal wings overhanging the sheet at a distance therefrom to form clenches with a plaster coating.

4. A reenforced building fabric comprising a flexible sheet of fibrous material, metal reenforcing wires woven at intervals through the sheet and forming undulations in the sheet crosswise of the wires, and auxiliary metal reenforcing and stiffening strips inserted between the wires and sheet and each formed with a longitudinal rib next to the sheet and with marginal flanges overhanging the sheet at a distance therefrom, the strips being formed between the sides of the ribs and the flanges with outwardly projecting beads which are rigidly fastened at intervals to the overlying wires.

5. A reenforced building fabric comprising a flexible sheet of fibrous material, metal reenforcing wires woven at intervals through

said sheet, and auxiliary reenforcing and stiffening members arranged crosswise of said wires and rigidly secured thereto at intersections of said members with said wires,
5 said wires being woven at closer intervals through the portions of said sheet between said members to provide additional bonds for plaster.

6. A reenforcing building fabric comprising a flexible sheet of fibrous material, metal reenforcing wires woven at intervals through said sheet and metal reenforcing and stiffening members extending under the wires and along one side of the sheet, said members being welded to said wires and having ribs projecting towards said sheet.

10 7. A reenforcing building fabric comprising a flexible sheet of fibrous material, metal reenforcing wires woven at intervals through said sheet and metal reenforcing and stiffening members extending under the wires and along one side of the sheet, said members having wings welded to said wires.

15 8. A reenforcing building fabric comprising a flexible sheet of fibrous material, metal reenforcing wires woven at intervals through said sheet and metal reenforcing and stiffening members extending under the wires and along one side of the sheet, said members having wings welded to said wires and having ribs projecting toward said sheet.

20 9. A reenforcing building fabric comprising a flexible sheet of fibrous material, reenforcing and stiffening members arranged upon said sheet, and reenforcing wires arranged crosswise of said members, said wire being woven through said sheet at a plurality of spaced intervals between said reenforcing members to prevent bulging of said sheet and to provide bonds for plaster, each wire being exposed for the major portion of its extent on the same side of the flexible sheet as the reenforcing and stiffening members, each wire directly engaging and being rigidly secured to the reenforcing and stiffening members at their intersections therewith.

25 40 45 In witness whereof I hereto affix my signature.

EDWIN D. CODDINGTON.
